UNITED STATES PATENT OFFICE.

ALBRECHT FREDERICH GEORG CARL PAUL JOSEF VON GROELING, OF NEW YORK, N. Y.,
ASSIGNOR TO ATLAS PROCESS COMPANY, INC., OF NEW YORK, N. Y., A CORPORATION
OF NEW YORK.

FRACTIONAL DISTILLATION OF CRUDE PETROLEUM AND OTHER HYDROCARBONS.

1,327,184.

Specification of Letters Patent.

Patented Jan. 6, 1920.

Application filed April 22, 1916. Serial No. 92,807.

To all whom it may concern:

Be it known that I, ALBRECHT FREDERICH GEORG CARL PAUL JOSEF VON GROELING, a subject of the Emperor of Austria, and a 5 resident of New York, in the county and State of New York, have invented certain new and useful Improvements in Fractional Distillation of Crude Petroleum and other Hydrocarbons, of which the following is a 10 full, clear, and exact description.

The invention that forms the subject of the present application relates to the distillation of crude petroleum or similar oils, and its chief object is to provide an improved 15 apparatus for the purpose whereby breaking up or "cracking" of distillates is practically, if not entirely, avoided, thus maintaining the natural composition of the same, with the best possible qualities as regards specific 20 gravity, flash-point, color, viscosity, and smell. A further object is the avoidance of evaporation losses in the distillation, formation of tarry substances (asphaltum and coke or carbon) in the later products, and 25 formation of so-called fire-paraffins. The process is either intermittent or continuous, as desired, and is performed entirely *in vacuo*, with the exception that the lighter fractions, such as gasoline and kerosene, 30 may if desired be distilled at ordinary pressure.

A convenient and effective apparatus for the purpose is illustrated, somewhat diagrammatically, in the accompanying drawings, in which—

Figure 1 is a plan view of the entire plant, omitting only the boiler or other generator by which steam is produced for heating the still or stills.

Fig. 2 is a side view of the same, from the bottom of Fig. 1, and

Fig. 3 is an end view from the left of Fig. 2.

Fig. 4 is a cross section, about on line 45 4—4 of Fig. 1.

Fig. 5 is a detail view of a barometric system for maintaining a substantially constant degree of vacuum over the apparatus by regulating the operation of the pump or 50 exhauster.

Fig. 6 is a vertical section of one of the stills.

Fig. 7 is a central horizontal section of the still shown in Fig. 6.

Fig. 8 is a cross section on line 8—8 of 55 Fig. 6.

Fig. 9 is an end view of the still shown in Fig. 6, from the left of the latter figure.

Fig. 10 is a central longitudinal section of the steam chamber from which steam, delivered by the boiler or generator, is supplied to the still or stills for heating the same.

Fig. 11 is a central longitudinal section of one of the vacuum receivers into which the 60 distillates are received for subsequent delivery to suitable storage tanks or vessels, not shown.

The number of stills provided may be one or more. In the plant illustrated I have 70 shown six, designated A, B, C, D, E, F. Each is in the form of a cylinder, arranged horizontally, with one or more vapor collecting domes a, b, c, d, e, f. The stills are arranged in cascade, and are connected by 75 pipes 10, 11, to the pipe 12 through which they are supplied with the crude oil, the latter being drawn in by the vacuum, produced as hereinafter described. In each case the pipe 11 is extended down to the 80 lower portion of the still (see Fig. 4) so that the residue can flow from one still to the next, and finally to the residue cooler 13. By means of valves 14, 15, in the pipes 10, 11, 12, the rate of flow can be accurately regulated. Ordinarily the valves 15 are closed, 85 so that the oil flows through all the stills in series, but any still can be cut out whenever desired by opening its valve 15 and closing its valves 14. A drain pipe 16, connected to 90 the bottoms of the stills through valved connections 17, is provided for the purpose of draining the stills into the vessel 13 when desired. The stills may be arranged on a level instead of in cascade; particularly if 95 the apparatus is to be used only for discontinuous working, in which case the connections 11 may be omitted.

The stills are heated by internal steam-coils 18, 19, Figs. 6, 7, 8, connected by valved 100 pipes 20, 21 to the steam main 22. By adjustment of the valves in said pipes 20, 21, the flow of steam to the heating coils, and hence the distilling temperature, indicated by thermometers, as T, Figs. 6 and 9, can 105 be regulated as desired for each still. To permit accurate temperature regulation the steam should be supplied to the main 22 at

constant pressure, and for this purpose it is delivered from the boiler or generator, not shown, to a steam chamber 23 through a reducing valve 24, and thence through a reducing valve 25 to the main. These reducing valves can be of any suitable construction and hence need not be described herein. They should, however, be provided with means for regulation of the pressure delivered, as for example the ball and lever construction indicated in Fig. 10. The reducing valves constitute convenient and effective means for maintaining a pressure (and hence temperature) in the steam chamber somewhat higher than in the still-heating coils but lower than in the steam-generator. On top of the steam chamber is a safety valve 26, a self-registering manometer 27, and a self-registering thermometer 28.

Water from condensation of steam in the heating coils 18, 19, is discharged through an outlet 29, Figs. 6 and 7, and delivered to a suitable receptacle, not shown. Sight-gages, as S, Fig. 9, are provided to indicate 25 the liquid level in the stills.

It is at times desirable to inject live steam into the contents of the stills, or one or more of them, and for this purpose each still is provided with a perforated pipe 30, Figs. 30 6 and 7, extending longitudinally near the bottom. These perforated pipes are connected by valved pipes 31 to a pipe 32 which is itself connected to the steam main 22 through a valve 33.

The stills are not set in masonry, but are 35 separately supported. They are, however, thoroughly heat-insulated by means of suitable jackets or coverings. To avoid confusing the drawings these insulating jackets 40 are not shown.

The distillation is fractional, and hence the temperatures vary accordingly, the lighter fractions coming off early in the series, for example in the stills A and B. Inasmuch as more or less of the heavier 45 fractions may come off at the same time, dephlegmators of any suitable kind are provided to receive the vapors from such stills, as for instance coolers of the tray type indicated at 34, Figs. 1, 2 and 3. The vapors from the domes *a*, *b*, enter the coolers at points near the bottom through pipes 35, and the light vapors or gases pass out at the top while the heavier are condensed 50 and flow back to the stills through valved pipes 36. The light vapors are conducted by pipes 37 to separate condensers 38, 39, more fully described hereinafter. From the remaining stills the vapors pass from the 55 domes to suitable air-cooled condensers composed of horizontal pipes 40, connected at one end to parallel pipes 41, which are in turn connected to similar pipes 42. The three pipes named are of successively smaller 60 diameter, and the first two are provided

with internal air pipes, as 43, 44, Fig. 1, open at the rear to the atmosphere and at the front provided with vertical stacks or chimneys 45, for creating a draft for drawing air through the internal pipes. Ordinarily the natural draft thus obtained is sufficient, without the use of fans or blowers. 70

From the condensers 40—41—42 the products flow through outlet pipes 46, 47, 48, to the coolers 49, 50, 51, 52. 75

The condensers 38, 39, and the coolers 49, 50, 51, 52, are of similar construction, and may be provided with internal pipes (not shown) for water circulation, connected through valves to a valved supply pipe 53. 80

From the condensers 38, 39, and coolers 49, 50, 51, 52, the products run through sight-glasses 54 to the vacuum receiving tanks 55, 56, 57, 58, 59, 60, which are connected together by a pipe 61. Valves 62 63, are provided so that the product of each still can be delivered to its own receiver, or the fractions or products of neighboring stills can be delivered to the same receiver, as desired. 85

The vacuum receivers are all like that shown in Fig. 11, which is in the form of a horizontal drum, provided at one end with a sight-gage 64 for showing the height of the liquid contents. When the contents of the receiver are to be removed the valves 65 and 66 are closed and the cock 67 is opened to admit air, after which the liquid can be drawn off through the valved outlet pipe 68. 90

As previously stated, all the elements of the apparatus,—the stills, coolers, condensers, and receivers,—are, preferably, under vacuum. For this purpose the vacuum receivers 55, 56, 57, 58, 59, 60 are connected (through the valves 66) to a pipe 69 which is in turn connected to a suitable vacuum 100 pump indicated at 70, driven by any convenient means as for example an electric motor 71. The pipe 69 is also connected to the residue receivers 71^a, so that the latter, and the residue cooler 13, with which they 105 are connected, are also under vacuum. In the case of the lighter fractions, for example those coming off in the stills A and B, the vacuum can be dispensed with, as by proper manipulation of the valves 65, 66, 67. 110

The use of vacuum permits low distilling temperatures, and the temperature used to obtain any given fraction depends upon the degree of vacuum under which the distillation is effected. It is therefore important 115 to have the vacuum under control, so that it can be kept constant. For this purpose any suitable and convenient controlling or regulating means, preferably automatic in action, as for example a device which is responsive 120 to change in the degree of vacuum and in accordance therewith varies the rate of operation of the vacuum pumps. Such a controlling system is illustrated diagrammatically in Fig. 5, and comprises a U-shaped 125

mercurial barometer 72, having a short leg which is open and a long leg which is connected to the vacuum pipe 69 by a valved pipe 73, Fig. 1. Sealed in the longer leg is 5 a series of platinum contacts, of any desired number depending upon how closely it is desired to regulate the vacuum. Three such contacts are shown, designated by 74, 75, 76, connected to relay magnets 77, 78, 79, 10 respectively, which latter are also connected through a battery 80 to a common return contact 81 in the wall of the barometer opposite contact 74. The contacts for the relay armatures are connected to taps brought out from a resistance connected in the circuit by means of wires 82, 83, while the armatures themselves are connected in parallel directly to the wire 82. Assuming that the vacuum is sufficient to bring the mercury up to the 20 contact 74, it will be seen that the circuit of magnet 77 is completed and the magnet energized, thereby raising its armature and cutting resistance into the circuit. If, now, the vacuum is insufficient to hold the mercury 25 at that point the column will fall, and when contact 74 is uncovered the magnet is de-energized, whereupon the resistance is cut out and the motor speeds up. On the other hand, if the mercury continues to rise it will 30 reach contacts 75 and thus cut more resistance into the circuit, causing the motor to slow down. The motor of course has the usual manually operated controller (not shown) so that its speed can also be controlled by hand to regulate the vacuum. 35

As previously stated, different temperatures are used in the stills, according to the products that are to be distilled out, low temperatures being permitted by reason of 40 the vacuum, and hence "cracking" or breaking up of distillates is practically eliminated. Accurate regulation of the temperature in the several stills is of the highest importance, and it is for this reason that steam-heating 45 is used. Other heating means, for example, electrical, may, however, be employed. The lightest product of course comes off in the still having the lowest temperature, say still A, the next in still B, and so on down the 50 series. The differentiation of products is in general sharp, so that the distillates are all finished products in that no further refining is required to fit them for the market, except that all are usually to be filtered through 55 suitable material, such as fullers' earth, or kieselguhr. If carefully done, this filtration suffices to make the distillates water white, or at least light and agreeable in color and smell. Washing with acid is unnecessary, 60 but if age should impart a yellowish tinge to any product a weak acid treatment is sufficient to bleach it out. The transition products between kerosene and lubricating oil are of high quality, usable as high grade 65 slightly viscous lubricants or for medical

purposes, as they are odorless and contain no noxious by-mixture. The lubricating oils can be converted into so-called Russian white oils with no further treatment but filtration, and are quite neutral and fit for bodily internal use. The final residue, (the so-called cylinder stock), can be distilled if desired, but simple filtration is usually sufficient. It contains no tarry matters, such as asphaltum. If paraffin wax is present in the crude oil 70 it is not increased by the production of so-called fire paraffins. The wax crystals are easily removed by filtration, as there is no fire paraffin to interfere. The whole treatment of the paraffin wax is simplified, since 75 it is confined to a narrow fraction of the lubricating oils, and the final residue (the cylinder stock) is free from paraffin wax. In most cases the paraffin wax can be removed by simple filtration, and, if necessary, a short sweating process. 80

In discontinuous or periodic working, the differentiation of the products is so sharp that redistillations need never be necessary; though between the kerosene fraction and 85 the so-called gas oil fraction, part of the distillate may sometimes appear with traces of a neighboring fraction, in which case the lighter can be blown out with live steam. 90

As will be readily understood, the temperatures and the degree of vacuum, needed for the best results, depend largely on the nature of the crude oil which is to be treated, and hence no definite rule can be given as to these particulars. They are, however, readily found by experience for any given oil. In general the vacuum should be as high as possible, that is, the pressure in the stills and other parts of the apparatus should be 95 as low as practicable. 100

It is to be understood that the invention is not limited to the details of apparatus and procedure herein specifically described, since these can be modified without departure from the spirit of the invention. 105

I claim:

1. An apparatus for distilling crude petroleum, comprising a plurality of stills; condensers connected with the respective stills; receivers connected with the respective condensers; vacuum-producing means connected with the receivers for creating a high vacuum in said stills, condensers, and receivers; automatic means for controlling the vacuum-producing means to maintain the degree of vacuum constant; steam-heating coils in the stills; a source of steam connected to the coils; automatic means for maintaining the steam in said source at constant pressure, and means for regulating the supply of steam to the coils, independently for each still, to accurately regulate the distilling temperature therein. 115
2. In apparatus for distilling crude petroleum, comprising a plurality of stills; 120
3. In apparatus for distilling crude petroleum, comprising a plurality of stills; 125
4. In apparatus for distilling crude petroleum, comprising a plurality of stills; 130

condensers connected with the respective stills; receivers connected with the respective condensers; vacuum-producing means connected with the several receivers, for 5 creating a high vacuum in the said stills, condensers and receivers; automatic means for controlling the vacuum-producing means to maintain the vacuum substantially constant in degree; and still-heating means permitting independent control of the distilling temperatures in the several stills.

3. An apparatus for distilling crude petroleum, comprising a plurality of stills; condensers connected with the respective 10 stills; receivers connected with the respec-

tive condensers; means for producing vacuum in the stills, condensers, and receivers; steam-heating coils in the several stills; a steam main; connections from the steam main to the steam-heating coils, having 26 means for regulating the supply of steam to the coils to accurately control the distilling temperatures of the stills independently; and means for supplying steam to said main at substantially constant pressure. 25

In testimony whereof I hereunto affix my signature.

ALBRECHT FREDERICH GEORG CARL
PAUL JOSEF VON GROELING.
